(57) **CLAIM**

(21) Appl. No.: **29/239,675**

The ornamental design for a dual dispenser package with single actuator, as shown and described.

(22) Filed: **Sep. 20, 2005**

DESCRIPTION

(51) LOC (8) Cl. **09-03**

FIG. 1 is an exploded view including overcap of the first embodiment of a dual dispenser package with single actuator;

(52) U.S. Cl. **D9/684**

FIG. 2 is a front view with overcap attached thereof;
FIG. 3 is a right-view, which is a mirror image of the left-side view thereof;

(58) Field of Classification Search D9/684,

FIG. 4 is a rear view attached thereof;

D9/424, 504, 521–530, 544, 560, 572–574,
D9/687, 694; D3/321; D7/605; D34/1;
222/137

FIG. 5 is a top view attached thereof;

See application file for complete search history.

FIG. 6 is a bottom view attached thereof,
